FLEXIBLE TELESCOPING GUIDE

Mark C. De Wolfe, Oakland, Calif.

Application May 12, 1934, Serial No. 725,407

7 Claims. (Cl. 61—73)

My invention relates to improvements in flexible telescoping guides or tracks, and it consists of the combinations, constructions and arrangements hereinafter described and claimed.

5 An object of my invention is to provide a flexible and telescoping guide or track which is designed for work of various sorts. The track can be supported by a mast, boom, or tower, and the mast can be swung into different angular positions for positioning the guide at the desired place. The legs of the guide are extensible and provide a runway for a hammer, cage or skip which can be varied in length in accordance with the work being done.

10 15 The legs of the guide comprise telescoping tubular members enclosing cables and the raising or lowering of these cables will change the length of the legs. It is obvious that the legs can be fully extended and the cables further extended so that the cables will project below the bottoms of the legs and the weights carried by the cables will come to rest on a supporting surface. For example in using the device in water the legs could be extended to their full 20 25 lengths and then the cables could be further extended until the weights would rest upon the ground.

The device is also designed to drive piling in water or on dry ground, and one form of the 30 device makes use of a guide ring disposed at the bottom of the legs for holding the lower end of the piling in position. Lugs are also carried by the legs and in turn support "strong backs".

The device is simple in construction and is 35 durable and efficient for the purpose intended. The device can be of permanent construction, or it may be made portable.

40 Other objects and advantages will appear in the following specification, and the novel features of the device will be particularly pointed out in the appended claims.

45 My invention is illustrated in the accompanying drawings forming a part of this application, in which

Figure 1 is a side elevation of the device showing it supported by a boom, mast, etc.;

Figure 2 is a section along the line 2—2 of Figure 1;

Figure 3 is a top plan view of the guide or track;

Figure 4 is a section along the line 4—4 of Figure 5, and shows a modified form of the invention;

Figure 5 is a side elevation of Figure 4;

50 Figure 6 is a top plan view of Figure 4;

Figure 7 is a section along the line 7—7 of Figure 4; and

Figure 8 is a section along the line 8—8 of Figure 4.

In carrying out my invention, I make use of 5 a boom 1 which is pivoted at 2 in a turn table 3, which in turn is rotatably carried by a support 4. The support 4 may be placed on the ground, or it may form a part of a movable body such as a crane or a barge. It is obvious that 10 the turn table 3 may be of the large type having a much greater radius between its center and the edge of the turn table than that shown in Figure 1. The turn table is of course supported by rollers not shown in order to give freedom of 15 movement.

The boom 1 can be swung into any desired angular position and may be supported in this position by top lift or boom lines 5 which are passed around pulleys 6 disposed near the top 20 of the boom. The lines 5 may be guide lines anchored to the ground or other support, or the lines may be attached to a reel, not shown, for permitting the swinging of the boom into different positions. Figure 2 shows the pulleys 6 as 25 being disposed on a shaft 7, and this shaft extends transversely through the boom and the pulleys are placed on the outside of the boom. Straps 8 or other suitable supports are secured to the boom and the shaft 7 is carried thereby. 30

The invention comprises an extensible guide or track consisting of two legs A and B. These legs are formed of telescoping tubes 9, 10 and 11. The tube 10 is slidable within the tube 9, and in like manner the tube 11 is slidable with- 35 in the tube 10. The top tubes 9 are interconnected by headers 12 and the sleeve fillers 13 are placed in the tops of the tubes 9 and have bores 14 for receiving guide cables 15. In like manner if desired the filler sleeves 16 and 17 may be 40 mounted in the tops of the tubes 10 and 11. Guide cables 15 pass through the sleeves 16 and 17.

The lower ends of the guide cables are connected to weights 18, and these weights have 45 reduced portions 19 receivable in the lower ends of the tubes 11. The reduced portions 19 abut against sleeves 20 carried by the lower ends of the tubes 11.

It will be seen from Figures 1 and 2 that guide 50 cables 15 are passed over pulleys 21, and may be wrapped around a drum or spool indicated dia-grammatically at 22 in Figure 1. It will be seen that the winding up of the cables 15 on the drum 22 will shorten the over-all length of the legs 55

A and B. Moreover, the lengthening of the cables will permit the legs A and B to lengthen until they are fully extended. The legs, when fully extended, can be rigidly secured together by 5 screws 23 which are passed through the tubes and through the sleeves. Two screws are used at each joint in order that they will be placed on either side of the guide cable, and the screws are flush with the outer surfaces of the tubes. 10 The lower ends of the tubes are rounded in order to provide a smooth guiding surface throughout the entire lengths of the legs.

The shaft 7 carries a plurality of pulleys 24 on the portion of the shaft disposed between the 15 sides of the boom 1, and these pulleys are used for supporting cables which, in turn, perform different duties. I have shown a cable 25 passed over the center pulley 24, and this cable is guided between idler pulleys 26 which are carried by 20 the header bars 12, see Figures 2 and 3. The cable is connected to a hammer 27 which has U-shaped guide members 28 that straddle the legs A and B. The upper edges of the U-shaped guides 28 are flared outwardly so that the raising 25 of the hammer from the tubular portion 10 to the tubular portion 9, for example, can be readily effected, the outwardly flared upper edges of the guides 28 riding over the rounded lower edges of the tubes 9. The same is true when the 30 hammer is raised from the tubes 11 to the tubes 10. In Figure 1, I show the cable 25 as being passed around a drum 29, and the drum is diagrammatically shown because it forms no part of my invention.

35 The cable 25 may support other devices than the hammer 27, such a skip or cage. I have indicated a hammer as one example, and this hammer could be used for driving piling, not shown. In case it is desired to reinforce the 40 legs A and B for holding them in spaced relation throughout their entire lengths, I provide a "strong back" 30 that is removably secured to lugs 31, which in turn have sleeve portions 32 that encircle the tubes 10. As many strong backs 45 as desired may be disposed along the legs and the shape of the strong backs is such as to permit the hammer 27 or other device to pass thereby.

I show a modified form of the invention in 50 Figures 4 to 8 inclusive. In this form the legs A and B consist of tubular sections 9, 10 and 11, as shown in the form already described. The principal difference of the second form is the provision of lugs that extend from the tubular 55 sections. The tubes 9 have lugs 33 disposed midway between their ends, and have lugs 34 positioned near the bottoms of the tubes. The tubes 10 have lugs 35 disposed near their bottoms and in like manner the tubes 11 have lugs 36 placed 60 at their lower edges. Flexible check lines 37 connect the lugs 34 and 35 together, and similar check lines 38 connect the lugs 35 and 36 together. The check lines permit the full extension 65 of the tubular sections and act as stops for preventing the entire removal of the sections from each other. In other words, the check lines take the place of the screws 23, and permit the ready foreshortening of the legs A and B when the cables 15 are wound upon the drum 70 29. The guide ring indicated generally at 39 and shown in Figures 4 and 8 is carried by the cables 15 and bears against the bottoms of the legs A and B. The guide ring can be made of any design and I have shown it as comprising two 75 members 40 and 41 pivoted at 42, and providing

a space 43 for receiving a piling 44. A number of openings 45 are provided in the ends of the members 40 and 41 disposed opposite to the pivot 42, and a pin may be inserted through the aligned openings 45 for varying the size 5 of the space 43. In this simple way the space can be made large enough to receive an object, such as the piling 44, and to guide the object.

The upper end of the piling 44 is received by the hammer 27 and the operation of driving the 10 piling into the ground by means of the hammer is accomplished in the usual manner.

The strong backs 46 in this form of the device are preferably secured to the lugs 33 to 36 inclusive, and are shaped so as to allow the 15 hammer to pass thereby, or any other object supported by the cable 25. As many strong backs as desired may be used.

The entire guide can be inclined at an angle 20 when it is desired to drive piling into the ground at a given angle, and to this end the guy lines (not shown) may be secured to any of the lugs 33 to 36 inclusive, and these guy lines attached to a supporting object so that the guides will be held at the desired angle or batter. 25 It will be noted from the drawing that the lugs 33 to 35 inclusive are secured to the outer surfaces of the tubes 9 and 10 and do not interfere with the U-shaped guides 28. The lugs 36 are passed through slots 47 in the tubes 11 30 and are welded to the filler sleeves 48, disposed in the bottom of the tubes.

The device can be used for all types of work and the cables 15 can be extended below the bottoms of the tubes 11 so that the weights 18 or 35 the guide ring 39 rests upon the ground. Also the length of the guides can be altered at will.

Material supply lines 48 are shown in Figure 1, and these extend from a drum indicated diagrammatically at 49, and are passed over idler 40 pulleys 50 carried by the top of the boom 1. The supply lines 48 are used for lifting material into position, such as the piles which are to be driven into the ground.

The header 12 is of course supported by a 45 cable 51 and the cable is passed over one of the pulleys 24 and is then wrapped around a drum 52. Additional openings can be provided in the tubes 9 and 10 for receiving the screws 23 in order to permit the tubes to be adjusted and 50 thus vary the overall length of the legs or tracks. The top section consisting of the tubes 9 can be used by itself if desired without the tubes 10 and 11. The cables 15 passing over the spaced pulleys 24 prevent the guide legs A and 55 B from whipping in the wind and becoming tangled. The screws 23 may also be used for connecting the tubes together in adjusted position in the form of the device shown in Figures 4 to 8 inclusive. 60

While I have shown only the preferred forms of my invention, it should be understood that various changes or modifications may be made within the scope of the appended claims without departing from the spirit of the invention. 65

I claim:

1. A telescoping guide comprising a pair of legs, telescoping tubes forming each leg, means for locking the tubes in adjusted position, guide cables disposed within and extending through 70 out the lengths of the legs, weights carried by the ends of the cables, and means for extending the cables below the bottoms of the legs so that the weights can rest on a supporting surface.

2. A telescoping guide comprising a pair of 75

- tubular telescoping members supported at their upper ends and free to swing at their lower ends, guide cables extending through the members and having supporting portions at their 5 lower ends for normally abutting the lower ends of the members, means for varying the length of the portions of the cables in the members for varying the overall length of the members, said means also being able to extend the cables beyond 10 the lower ends of the members, the supporting portions constituting weights and designed to rest on the ground for holding the exposed portions of the cables projecting below the members in alignment with the members.
- 15 3. A telescoping guide comprising a pair of telescoping legs, a header securing the tops of the legs together, means for supporting the header in a desired position, filler sleeves mounted in the legs, guide cables mounted in the legs and extending through the sleeves, said cables supporting the bottoms of the legs, and means for varying the lengths of the cables for varying the lengths of 20 the legs.
4. A telescoping guide comprising a pair of telescoping legs, a header securing the tops of the legs together, means for supporting the header in a desired position, filler sleeves mounted in the legs, guide cables mounted in the legs and extending through the sleeves, said cables supporting the bottoms of the legs, and means for varying the lengths of the cables for varying the lengths of the legs, and strong backs adjustable 25 along the legs for holding the legs in spaced relation.
5. A pair of extensible guides each comprising a plurality of telescoping tubular members, a header connecting the guides together, lugs carried by the members, and flexible check lines interconnecting the lugs for limiting the extension of the 5 legs beyond a predetermined length, and strong backs removably secured to the lugs for spacing the guides from each other.
6. An extensible guide comprising parallel tracks formed of telescoping tubular members, a 10 header connected to the tops of the tracks, guide cables extending through the tubular members, a guide ring supported by the cables and being disposed at the bottom of said tracks, an object movable between the tracks, U-shaped guides carried 15 by the object and being slidable along the tracks, said object being designed to bear against the top of a pile, the other end of the pile being passed through the ring.
7. An extensible guide comprising parallel 20 tracks formed of telescoping tubular members, a header connected to the tops of the tracks, guide cables extending through the tubular members, a guide ring supported by the cables and being disposed at the bottom of said tracks, an object movable between the tracks, U-shaped guides carried 25 by the object and being slidable along the tracks, said object being designed to bear against the top of a pile, the other end of the pile being passed through the ring, lugs carried by the tubular 30 members, and flexible check lines connected to the lugs for limiting the extension of the tracks.

MARK C. DE WOLFE.
